US00D507015S

(12) **United States Design**
Fjermestad et al.

(10) Patent No.: US D507,015 S
(45) Date of Patent: ** Jul. 5, 2005

- (54) **ELECTRONIC CALORIE INFORMATION AND CALORIE CONSUMPTION CALCULATOR**

(76) Inventors: **Brian A. Fjernestad**, 69733 240th St., Albert Lea, MN (US) 56007; **Sidney L. Solum-Curtis**, 17671 Southridge Ct., Minnetonka, MN (US) 55345

(**) Term: **14 Years**

(21) Appl. No.: **29/202,912**

(22) Filed: **Apr. 8, 2004**

(51) **LOC (8) Cl.** **18-01**

(52) **U.S. Cl.** **D18/7**

CLAIM

We claim the ornamental design for an electronic calorie information and calorie consumption calculator, as shown and described.

DESCRIPTION

FIG. 1 is a perspective view of an electronic calorie information and calorie consumption calculator.

(74) *Attorney, Agent, or Firm*—Donald R. Schoonover

(57) **CLAIM**

We claim the ornamental design for an electronic calorie information and calorie consumption calculator, as shown and described.

DESCRIPTION

FIG. 1 is a perspective view of an electronic calorie information and calorie consumption calculator showing our new design;

FIG. 2 is a top plan view thereof;

FIG. 3 is a bottom plan view thereof;

FIG. 4 is a left side elevational view thereof;

FIG. 5 is a right side elevational view thereof.

FIG. 6 is a front elevational view thereof.
